APPARATUS FOR JOINING THE WEBS OF
PAPER ROLLSPaul Dietrich, Augsburg, Germany; vested in the
Alien Property CustodianApplication May 24, 1940, Serial No. 337,038
In Germany June 24, 1939

4 Claims. (Cl. 242—58)

This invention relates to a device for joining paper rolls by sticking a new roll to a running-down web, the new roll, disposed in a rotary frame, being brought up to the speed of the running-down web and, by turning the frame, into a position of which the sticking operation is performed. This is done by means of a pressure applying brush at the end of a lever actuated by a piston or pistons which are moved by pneumatic or hydraulic pressure controlled by an electromagnetically operated piston slide-valve or a valve system.

The present invention constitutes an improvement of a device of the type outlined above and takes into consideration that when the running-down roll is swung out of operating and into sticking position for the new roll the brush must be moved out of the range of the running-down roll and later on brought again as closely as possible to the running-down web. This is necessary, since in view of a web speed of approximately 6-8 meters per second exact operation of the sticking means is insured only by rapid action. As the release of the sticking operation depends upon the position of the joining point on the new roll, even tenths of a second will matter and the brush must therefore be in direct contact with the running-down web prior to sticking. Such an arrangement is suitable also because it reduces fluttering of the running web and thereby insures sticking.

In a known construction of this class the cylinder for actuating the lever for the brush is fixed to the machine frame. To bring about the to and fro motion of the brush preceding the sticking operation the shaft for the lever is moved separately with the result that the piston, particularly during application of the brush to the running-down web, is displaced to such an extent that an empty space is produced on one side of the piston and had to be filled with air or liquid during the subsequent actuation of the sticking means. Experiments have shown, however, that this involves a loss of time great enough to prevent operation of the sticking means at the requisite speed.

According to the present invention, these drawbacks are eliminated by mounting the cylinder on an arm that is movable about the shaft for the lever supporting the brush. At the actuation of this arm, the motion thereof will be transmitted through the piston, piston rod and lever to the shaft for the latter and the brush applied to the web without relative displace-

ment of the piston and cylinder and without the formation of a dead space.

In a particularly simple constructional embodiment of the invention only a single cylinder having a piston working against spring action is used. The movable arm on which the cylinder is mounted may be actuated at will, preferably by means of a pawl-operated handwheel and eccentric.

10 The invention is illustrated by way of example in the accompanying drawing, in which

Fig. 1 is an elevation of a three-roll reel in association with an improved apparatus for joining the webs of the respective rolls;

15 Fig. 2 is an enlarged detail view similar to the right-hand portion of Fig. 1 and taken along line 2—2 in Fig. 3, the supporting frame structure being omitted;

20 Fig. 3 is a sectional detail view looking at the left-hand portion of Fig. 2;

Fig. 4 is a detail view showing the pawl for controlling the position of the handwheel and eccentric.

Referring to the drawing, the three-roll star 25 2 is rotatably mounted in the bearings of floor stand 1. One leg of star 2 carries the running-down roll 3, from which a web 4 of paper or the like is unwound during operation. When the web 4 has become substantially exhausted from roll 3, the present invention is employed for sticking or adhesively securing the exhausting web to a new roll 5, said roll 5 being mounted upon another leg of star 2.

In Fig. 1, the web on the running-down roll 3 has almost become exhausted, and is positioned so that the web of the succeeding roll 5 may be adhesively secured to the exhausting web. The roll 3, when full, previously occupied the position now occupied by roll 5, in Fig. 1. During the unwinding of roll 3, however, the reel 2 was rotated in a clockwise manner through an angle of 120° to the position shown, thus moving the periphery of the full roll 5 beneath band drive 60 and also into close proximity to the web 4 extending from roll 3. A brush 6 is employed for adhesively securing the exhausting web 4 to the web of new roll 5, and a knife 18 is employed for severing the running-down web.

The apparatus for producing the above-mentioned splicing operation is not a part of the present invention; however, a full explanation of such a device is given in my copending application, Serial No. 319,192, filed February 16, 1940.

As heretofore stated, it is not only necessary to move the brush 6 out of range of the running-

down roll 3 as said roll passes from upper operating position to the lower position shown (Fig. 3), but it is also necessary to produce this brush movement without affecting the sensitivity of the brush operating means.

Referring to Figs. 1 to 4 inclusive, the invention resides in the following:

The brush 6 is arranged on a lever 7 connected with the shaft 9 which through the lever 10 keyed thereto is moved by the piston 11 against the action of the spring 104. According to the invention, the cylinder 100 is mounted on an arm 101 loosely rockable about the shaft 9 and moved by a lever 102 eccentrically connected at 105 with a handwheel 103 controllable by a pawl 103a, which pawl yieldingly engages ratchet 103b. By turning the handwheel 103, the arm 101 and thereby the shaft 9 are adjusted without causing any variation in the position of the piston 11 in the cylinder 100. Thus, the lever 7 and brush 6 can be readily swung away from or towards the path of travel of the web to permit rotation of the rotary frame and permit the brush to be brought quite close to the web so that it can be instantly operated by the fluid pressure piston when pasting is to take place under automatic control at the proper instant. As the automatic control of the brush is effected by an electrically controlled fluid pressure piston and cylinder construction, the pasting takes place without jar or shock and with a very accurate control for the exact time of pasting.

What I claim is:

1. In a device for sticking a running down paper web to a new roll of paper, in combination, a rotary carrier for the running down roll and the new roll, operable to bring the new roll to position for sticking, a pressure applying sticking member, a pivoted lever carrying said member, a fluid pressure cylinder having a piston connected to said lever for swinging the lever about its pivot axis, means for supplying fluid pressure to said cylinder to operate the piston, a movable arm carrying said cylinder, and means for operating said arm to withdraw or advance the sticking member relative to the rotary carrier.

2. In a device for sticking a running down pa-

per web to a new roll of paper, in combination, a rotary carrier for the running down roll and the new roll, operable to bring the new roll to position for sticking, a pressure applying sticking member, a pivoted lever carrying said member, a fluid pressure cylinder having a piston connected to said lever for swinging the lever about its pivot axis, means for supplying fluid pressure to said cylinder to operate the piston, a movable arm carrying said cylinder and having a pivotal support coaxial with the pivot axis of said lever, and means for operating said arm to withdraw or advance the sticking member relative to the rotary carrier.

3. In a device for sticking a running down paper web to a new roll of paper, in combination, a rotary carrier for the running down roll and the new roll, operable to bring the new roll to position for sticking, a pressure applying sticking member, a lever carrying said member and having a fixed fulcrum axis, a fluid pressure cylinder having a piston operable therein and connected to said lever to swing the lever about its fixed axis, means for supplying fluid pressure to said cylinder to operate the piston, a movable arm carrying said cylinder and pivotally movable about said fixed axis, and means for operating said arm to withdraw or advance the sticking member relative to the rotary carrier.

4. In a device for sticking a running down paper web to a new roll of paper, in combination, a rotary carrier for the running down roll and the new roll, operable to bring the new roll to position for sticking, a pressure applying sticking member, a pivoted lever carrying said member, a fluid pressure cylinder having a piston connected to said lever for swinging the lever about its pivot axis, means for supplying fluid pressure to said cylinder to operate the piston, a movable arm carrying said cylinder and having a pivotal support coaxial with the pivot axis of said lever, a hand wheel, an eccentric operated by said hand wheel, and an eccentric crank operated by said eccentric and connected to said arm for swinging the arm on its pivotal support.

PAUL DIETRICH.
